UNITED STATES PATENT OFFICE.

EDWARD KRAHENBEIHL AND PAUL RICE, OF ALLEGHENY, PENNSYLVANIA.

COVERING FOR STEAM BOILERS, PIPES, AND OTHER HEATED SURFACES.

SPECIFICATION forming part of Letters Patent No. 293,752, dated February 19, 1884.

Application filed October 10, 1883. (No model.)

To all whom it may concern:

Be it known that we, EDWARD KRAHENBEIHL and PAUL RICE, of Allegheny, in the county of Allegheny and State of Pennsylvania, have invented certain new and useful Improvements in Coverings for Steam Boilers, Pipes, and other Heated Surfaces; and we do hereby declare the following to be a full, clear, and exact description of the invention, such as will enable others skilled in the art to which it appertains to make and use the same.

Our invention relates to an improvement in coverings for steam pipes, boilers, &c., the object being to provide a covering or jacket which shall be so constructed that air-spaces shall be formed at intervals between the covering or jacket and boiler or pipe, and thus secure a more perfect non-conductor of heat; and with this end in view our invention consists in certain novel features of construction, as will be hereinafter described, and pointed out in the claims.

In the accompanying drawings, Figure 1 is a view in perspective of a jacket or covering embodying our invention. Fig. 2 is a similar view of our improvement applied to a pipe. Fig. 3 is a modification.

A represents a covering or jacket, made of any desired material, but preferably composed of layers of paper secured together, or paper-pulp, the inner surface of the same being lined with asbestos, plaster, or other desired fire-proof material when it is desired that the covering withstand a great degree of heat, said cover being also cut longitudinally to more

easily apply it to the pipe B, the edges being secured in any desired manner. The covering is fluted or provided with corrugations C, the same being formed when the covering is compressed into shape. By these means air-spaces E are formed at intervals between the covering and the pipe or boiler, only a small portion of the covering coming in contact with said pipe or boiler, and thus presenting but a small surface for the transmission of heat, the air-spaces E forming a good non-conductor.

The corrugations may be formed in any desired shape, one form being shown in Fig. 3 of the drawings, and may also be made of any desired size.

Having fully described our invention, what we claim as new, and desire to secure by Letters Patent, is—

A covering for steam boilers, pipes, &c., consisting of layers of paper firmly united together, or paper-pulp, the said covering being lined or coated on its inner surface with asbestos, and the said lining and covering being fluted or corrugated longitudinally, whereby air-spaces are formed between the boiler and covering, substantially as set forth.

In testimony whereof we have signed this specification in the presence of two subscribing witnesses.

EDWARD KRAHENBEIHL,
PAUL RICE.
